MOISTENING BRUSH AND HOLDER

August C. Hummel, Cincinnati, Ohio

Application October 25, 1945, Serial No. 624,368

6 Claims. (Cl. 91—54.4)

1

My invention relates to the provision of a piece of office equipment which provides a well for containing water, a brush which is moistened by the water, and a guide plate and support for labels or the like which are to be moistened.

One of the objects of my invention is to provide for a support and guide for labels to be moistened which can be swung up and down as if hinged, but can be lifted entirely away from the casing that forms the water container, thus making the interior of the casing available for cleaning out or filling.

Another object of my invention is to use the support and guide as a cover for the casing in storage, and during shipment and use. Another object is to provide by means of the structure of the casing for a means of supporting the moistening brush in two positions. In one of these, the support and guide will rest on the top of the brush at the elevated portion thereof under which a label is to be slipped for moistening it. In the other of these positions the cover lies against the side of the brush leaving its upper edge exposed for moistening the fingers or applying the gummed edge of some article which is not of the size to slip under the elevated portion or guide element of the supporting plate.

The device of my invention in its preferred form is inexpensive and sturdy, consisting of a single casting as the casing, water well and brush and label support, plus a cover plate which is the label support, plus a brush of the proper dimension. No parts are held together so that all can be cleaned separately, yet in use the parts behave as if they were really held together in an effective unit.

I have illustrated in the drawings an example of my invention in its preferred form and will describe it in detail and here make reference to the appended claims for the novelty inherent in the structure.

In the drawings:

Figure 1 is a plan view of the device.

Figure 2 is a section on the line 2—2 of Figure 1.

Figure 3 is a like section showing the brush, which is in storage in Figure 2 in position for moistening labels, with the cover plate properly placed for this operation.

Figure 4 is still another like section showing the brush in position for general moistening with the cover plate in the position required upon this adjustment of the brush.

Figure 5 is a perspective view of the cover plate.

2

Figure 6 is a perspective view of the brush.

The casing of the device, as already suggested, is preferably a single casting having a hollow rectangular body 1 with a cross partition 2 therein, said partition having a slot 3 therein which permits water in the casing to communicate freely between the two parts of the casing divided by the partition. The casing side walls are formed with internal ribs 4, 5, 6 and 7 in this instance four in number, two located on each side of the partition and terminating at the upper end below the upper edges of the side walls, the forward two ribs on opposite side walls being somewhat longer than the other two ribs. Since the cover plate rests on these ribs and the casing is slanted upwardly toward the one end, the cover plate will lie generally parallel with the tops of the casing walls.

The cover plate 8 is flanged on its sides at 9, the flanges being arranged to fit into the top of the casing and rest on the tops of the four ribs, as above noted. In the illustrated form the flanges are formed by angle iron pieces riveted or screwed to the main cover. They may be integral instead. The pieces 9 extend beyond the main body of the plate which is the label support and serve to mount on their top surfaces the guide plate portion 10 of the cover. The result of this construction is that the guide plate is elevated above the label supporting plate portion of the cover and labels laid on the main or support plate portion can be slid under the guide plate portion. A label 11 is shown as being so manipulated in Figure 3. The level of the guide plate portion is also higher than the end wall of the casing to permit passage of the label.

As shown by Figure 1 and Figure 2, when the brush is not in the casing or else is laid down flat on the median partition the cover rests in place within the top of the casing, enclosing it.

There are two ribs 12, 12 on the rear wall of the casing which project inwardly and serve along with the central partition to support the brush in a generally horizontal position as shown in Figure 2. The brush 13 (Figure 6) may be of any desired construction, its important feature being its dimensions. It is preferably backed with a metal plate 13a to give it stiffness in its several positions in the device.

When it is desired to use the brush for labels (Figure 3) the cover plate is tilted upwardly, which can be done without lifting it away, since it will pivot on the two rearward supporting ribs 4 and 7, and the brush is arranged in the casing so as to rest on the cross partition 2 and abut

with its inner edge the two ribs 12. The cover plate is then lowered, whereupon the proportions are such that, as already noted, the higher level guide plate will rest on the top of the brush. A label such as at 11 can be supported on the main plate of the cover, and pushed with the fingers under the guide plate and be thoroughly moistened by the brush, which will draw water up from the casing. The water is indicated at 14 in Figures 3 and 4.

When the device is to be used for general moistening, the cover is again moved up hingedly as before, and the brush lifted and put into position abutting the partition at its inner end and resting on the forward wall of the casing at its upper end. When the cover plate is dropped into place it will then (Figure 4) engage the side of the brush leaving its tip available for moistening the fingers or the gummed portion of some article as indicated at 15 in Figure 4.

There are thus three positions of the brush, and the cover telescopes into the top of the casing and by means of engagement of its flanges on the side wall ribs will move hingedly on the rear ribs as a pivot, although it can be lifted off at any time.

It is apparent that variations in structure may be adopted and still obtain the various features of the device as now described.

Having thus described in detail an example of my invention, what I claim as novel therein, and desire to secure by Letters Patent, is:

1. In a device of the character described, a casing having a front and rear wall and side walls to hold liquid and containing a brush, a cover for said casing of a smaller width than the casing so it may rest within the side walls thereof, projections within the casing on which the cover rests, a pair of them located adjacent the rear wall of the casing on the side walls thereof, whereby the cover may pivot on said projections as if hinged, and projections within said casing forming abutments for holding the brush in two positions, one with its upper edge within the casing near the top, and the other with its edge lapping over the top front wall of the casing, said cover having a raised portion beneath which labels can be guided for contact with the brush in the first of its positions, the casing being of a cross sectional dimension sufficient to contain the brush when the latter is in horizontal position.

2. The combination of claim 1 in which the projections noted for the brush comprise a par-

tition extending upwardly within the casing, having passage therethrough for flow of liquid from the two sides thereof, the proportions of the partition being such that when the brush is laid horizontally on the partition, the cover may come down entirely within the casing.

3. The combination of claim 1 in which the projections noted for the brush comprise a partition extending upwardly within the casing, having passage therethrough for flow of liquid from the two sides thereof, the proportions of the partition being such that when the brush is laid horizontally on the partition, the cover may come down entirely within the casing, and the projections within the casing including further projections located so as to engage the inner end of the brush when tilted and supported on the partition noted, said partition being located so as to serve as the abutment for the inner end of the brush when tilted to engage the forward wall of the casing and project slightly therefrom.

4. The combination of claim 1 in which all projections are cast into the structure of the casing.

5. The combination of claim 1 wherein the brush is of substantially the width of the casing and of a length to bring its outer edge to the positions noted.

6. A cover plate adapted to be supported within a water containing casing and being of less width than the casing, said plate having angle pieces of less length than the casing secured thereto and providing flanges for projecting into the casing, said angle pieces projecting beyond the plate, a second plate mounted on the projecting portions above, beyond and parallel to the forward edge of the first mentioned plate so as to provide a guide under which objects laid on the first mentioned plate may be slipped.

AUGUST C. HUMMEL.
